CUSPIDOR LINER

Fred E. Rohrmann, Milwaukee, Wis.

Application September 17, 1934, Serial No. 744,351

5 Claims. (Cl. 4—285)

This invention relates to cuspidor liners and more particularly to a liner for cuspidors which may be discarded after use.

An object of the invention is to provide a cuspidor liner which may be economically fabricated and which will have features of easy disposal.

Another object of the invention is to arrive at a cuspidor liner with means for sanitary removal from the cuspidor proper.

Other and further objects of the invention will appear as the description proceeds; reference being had to the accompanying drawing in which:—

15 Fig. 1 is a perspective view of a cuspidor liner embodying my invention.

Fig. 2 is a view in vertical section similar to Fig. 1 showing the wire carrier.

Fig. 3 is a plan view in elevation of the preferred form.

Fig. 4 is a vertical sectional view of a modified form of the invention, and

Fig. 5 is a plan view of the form shown in Fig. 4.

Referring more particularly to the drawing, 25 the numeral 10 refers to the base portion of the cuspidor liner which is pan shaped and has its upper marginal edge 11 turned outwardly to support the frustro conical portion 12. The lower edge 13 of the frustro conical section 12 projects 30 inwardly over the upper margin of base 10. Adjacent edge 13 is an orifice 14 for the convenient emptying of liquids from the device. A wire member 15 is fixed by its ends 16 and 17 to the portion 12 of the device adjacent the edge 13 and 35 forms an arc across the center of the liner whereby the latter may be lifted by means of a hooked implement, and may then be discarded as refuse.

A modification of the above form is shown in Fig. 4 in which the portion 12 carries a pair of eyes 18 and 19 which may be engaged by appropriate instruments for removal of the liner. It will be understood that the device is capable 40 of various modifications in structure and design

without departing from the spirit of the invention, within the scope of the appended claims.

Having thus described my invention, what I claim and desire to secure by Letters Patent of the United States, is:—

5 1. A cuspidor liner comprising a pan shaped basal portion, a frustro conical portion mounted thereon at the top and means attached across the bottom of said frustro-conical portion for lifting said liner from the receptacle.

10 2. A cuspidor liner comprising a pan shaped basal portion, a frustro conical portion mounted thereon at the top, and a wire extended between opposite sides of the lower edge of said frustro-conical portion and affixed thereto for removal 15 of the same from the receptacle.

20 3. A cuspidor liner comprising a pan shaped basal portion, a frustro conical portion at the top thereof overlapping within the pan shaped portion and having an orifice in said overlapping portion adjacent and within the upper edge of the pan shaped portion, and a wire member extending across the center thereof.

25 4. A cuspidor liner comprising a pan shaped basal portion, a frustro conical upper portion 25 at the top thereof overlapping within the pan shaped portion and having an orifice in said overlapping portion adjacent and within the upper edge of the pan shaped portion, and a pair of eyes oppositely disposed on the upper side of said 30 frustro conical portion adjacent the lower opening thereof for removal of said liner from a receptacle.

35 5. A cuspidor liner comprising a pan shaped basal portion, a frustro-conical portion at the top thereof overlapping within the pan shaped portion and having an orifice in said overlapping portion adjacent and within the upper edge of the pan shaped portion, and a wire member attached to opposite sides of the lower portion of 40 said frustro-conical member for removal of said liner from a receptacle.

FRED E. ROHRMANN.
